J. J. Groden
WITNESS:

UNITED STATES PATENT OFFICE.

JOHN J. GRODEN, OF PHILADELPHIA, PENNSYLVANIA.

FOLDABLE WRINGER.

Original application filed July 22, 1922, Serial No. 576,827. Divided and this application filed July 20, 1923. Serial No. 652,802.

This invention relates to improvements in wringers and contemplates as a primary object the construction of a wringer which shall be both rotatable and foldable, the folding 5 not to affect the rotatability of the wringer.

This application is a division of my pending application Serial No. 576,827, filed July 22, 1922, which has matured into Patent No. 1,564,136 of December 1, 1925, and is 10 directed exclusively to the wringer mechanism as shown in that application.

One of the principal objects of the invention is to provide a swinging and foldable wringer with the usual drain boards attached 15 thereto which may be folded within the cabinet of a washing machine.

Another object of the invention is to produce a wringer of this nature which can be folded without the necessity of throwing any 20 of the gearing out of operation, whereby the standard construction of wringer may be used, and the loose connections and wear due to having to throw gears into and out of mesh, may be eliminated.

Another object of the invention is to produce a device of this nature which shall be 25 simple of construction, comparatively inexpensive to manufacture, and highly efficient for the purpose for which it is designed.

With these and other objects in view, the invention resides in certain novel features of construction and combination and arrangement of parts, the essential features of which are hereinafter fully described, are 30 particularly pointed out in the appended claim, and are illustrated in the accompanying drawing, in which:—

Figure 1—is a perspective view of a portion of the cabinet and the wringer mounted 40 thereon.

Figure 2—is a vertical sectional view showing a side elevation of the drive mechanism and showing the wringer folded in full lines and in upright position in dotted lines.

Figure 3—is a top plan view of the device, showing the oscillatable positions of the wringer.

Figure 4—is a vertical sectional view of the gear box of the wringer and the adjacent 50 parts.

Like characters of reference refer to like parts in all views.

Referring to the drawing in detail, 17 represents a portion of the washing-machine

cabinet with which the wringer is to be associated and on which it is to be mounted. 55 Mounted on this framework or cabinet is a motor 32 of the usual type utilized for driving washing machines and including a motor shaft 33 which may be connected by any suitable gearing to drive the upright shaft 36. The shaft 36 is supported in upright position by any suitable bearings and carried at its upper end a bevel gear 87 adapted to mesh with either of the bevel gears 90 or 91 which 60 are slidably keyed to the wringer operating shaft 88. The gears 90 and 91 are preferably formed integral and provided centrally with an annular groove 92 which receives the end of a member 93 carried by a shaft 94 65 having a control handle 95.

It will be readily understood that by the above described mechanism, the direction of drive of the shaft 88 may be reversed, and the wringer turned in either direction desired at the will of the operator. The gears 90 and 91 are housed within a gear box 82 mounted on the bracket 35, said box also has bearings for the wringer operating shaft 88.

The gearing from the shaft 88 to the 75 wringer rolls 84 is indicated at 75 in Figure 3, and is the usual operative gearing of a wringer mechanism. The wringer frame 83 is mounted for partial rotation about the circumference of the trunnion 85 and is held 80 in any one of a plurality of positions by a suitable spring influenced vertical plunger 98 engaging one of a plurality of recesses 98' in the trunnion 85. Inasmuch as the wringer is movable about the circumference 85, and the axis of the wringer operating or driven shaft 88, it will 85 be readily seen that none of the pinions are thrown out of mesh by the rotating of the frame 83 from the vertical or operating to 90 the horizontal or folded position and that the folding is effected entirely independent of the relation of the operating mechanism.

The wringer is also rotatable on and about the axis of the shaft 36. This rotatable, adjustable mounting of the wringer, consists of a depending hub 96 included in the bracket 35 and which is rotatable on the shaft 36 and within the stationary bearing sleeve 37. The hub 96 is provided intermediate its ends 100 with a plurality of locating recesses 99 any one of which may selectively register with an aperture 100 in the bearing sleeve 37.

Said sleeve and the casing associated with the wringer, are therebetween provided with a suitable horizontal spring influenced plunger 97, for engagement in any one of the recesses 99 for the purpose of holding the entire wringer structure in a selected rotatably adjusted position.

While I have described what I deem to be the most desirable embodiment of my invention, it is obvious that many of the parts may be varied without in any way departing from the spirit of my invention, and I therefore do not limit myself to the exact details of construction herein shown nor to anything less than the whole of my invention limited only by the appended claim.

What I claim is:—

A foldable wringer comprising a laterally extending supporting bracket, a gear box on said bracket, a bearing hub integral with and depending at right angles from said bracket, a stationary bearing sleeve, said

bearing hub being rotatably adjustable in said bearing sleeve, a drive shaft disposed in said hub, means co-operable between the bearing sleeve and the hub for holding the head in different selected positions and retaining the wringer against rotation about the drive shaft, a bevel gear secured to the upper end of said drive shaft and extending into said gear box, a laterally extending driven shaft rotatably supported in said gear box, a pair of bevel gears on a portion of said driven shaft located in said gear box, means for shifting the gears on the driven shaft, a vertical spring influenced plunger with means to retain said wringer frame in a selected position, and a pinion on said driven shaft between said gear box and wringer frame for maintaining a constant mesh with and driving a set of wringer gears.

In testimony whereof I affix my signature.

JOHN J. GRODEN.
